UNITED STATES PATENT OFFICE.

HUNLEY E. SEATON, OF LOS ANGELES, CALIFORNIA.

DESIGN FOR A COMBINED LOOSE-LEAF DESK PAD AND CALENDAR HOLDER.

Application filed March 19, 1928. Serial No. 25,916. Term of patent 14 years.

To all whom it may concern:

Be it known that I, HUNLEY E. SEATON, a citizen of the United States, residing at Los Angeles, in the county of Los Angeles and State of California, have invented a new, original, and ornamental Design for a Combined Loose-Leaf Desk Pad and Calendar Holder, of which the following is a specification, reference being had to the accompanying drawing, forming a part thereof.

Figure 1 is a perspective view of a combined loose leaf desk pad and calendar holder showing my new design.

Fig. 2 is an end view of the same looking

from the left hand end shown in Fig. 1.

Fig. 3 is a side elevational view of my new design looking toward the right from the left hand side of Fig. 2.

Fig. 4 is a side elevational view as viewed from the rear side of Fig. 3.

I claim:

The ornamental design for a combined loose leaf desk pad and calendar holder, as shown.

Signed at Los Angeles, in the county of Los Angeles, and State of California, this 13th day of March, 1928.

HUNLEY E. SEATON.
